Primary Examiner — Rosemary K Tarcza*Assistant Examiner* — Christy M Nemeth**CLAIM**The ornamental design for an arc fault current interrupter,
substantially as shown and described.**DESCRIPTION**FIG. 1 is a top perspective view of an arc fault current
interrupter;

FIG. 2 is a bottom perspective view thereof;

FIG. 3 is a top view thereof;

FIG. 4 is a bottom view thereof;

FIG. 5 is a right side view, with the left side view a mirror
image thereof;

FIG. 6 is a front view thereof; and,

FIG. 7 is a rear view thereof.

The broken lines shown in the views and the structures they
depict form no part of the claimed design.**1 Claim, 6 Drawing Sheets**(56)
